CLAIM

I claim the ornamental design for the door bell guard, as shown and described.

DESCRIPTION

FIG. 1 is a perspective view of a door bell guard showing my new design;

FIG. 2 is a right side elevational view thereof, the left side elevational view being the same as said right side elevational view;

FIG. 3 is a front elevational view thereof;

FIG. 4 is a rear elevational view thereof;

FIG. 5 is a bottom plan view thereof;

FIG. 6 is a top plan view thereof; and,

FIG. 7 is an exploded view thereof, showing the two components of my new design for clarity of illustration.

The broken line showing of a door bell is for illustrative purposes only and forms no part of the claimed design.
